UNITED STATES PATENT OFFICE

96,568

DESIGN FOR A HYDRAULIC JACK

Richard W. Werner, Milwaukee, Wis.

Application May 13, 1935, Serial No. 56,810

Term of patent 14 years

To all whom it may concern:

Be it known that I, Richard W. Werner, a citizen of the United States, residing at Milwaukee, in the county of Milwaukee and State of Wisconsin, have invented a new, original, and ornamental Design for a Hydraulic Jack, of which the following is a specification, reference being had to the accompanying drawing, forming part thereof.

In the drawing:

Figure 1 is a perspective view of a hydraulic jack, showing my new design.

Figure 2 is a front elevational view.

I claim:

The ornamental design for a hydraulic jack as shown.

RICHARD W. WERNER.
